UNITED STATES PATENT OFFICE.

JOHN NAZEL, OF PHILADELPHIA, PENNSYLVANIA, ASSIGNOR TO HIMSELF
AND EDWARD L. BAILEY, OF PHILADELPHIA, PENNSYLVANIA.

CREASING-MACHINE.

No. 805,576.

Specification of Letters Patent.

Patented Nov. 28, 1905.

Application filed May 18, 1904. Serial No. 208,523.

To all whom it may concern:

Be it known that I, JOHN NAZEL, a citizen of the United States of America, residing in the city and county of Philadelphia, in the 5 State of Pennsylvania, have invented a certain new and useful Improvement in Creasing-Machines, of which the following is a true and exact description, reference being had to the accompanying drawings, which form a part 10 thereof.

My invention relates to machinery for creasing heavy paper or cardboard such as is used in the manufacture of paper boxes, my object being to provide improved means for effecting such creasing or scoring and also effecting the severance of the sheet into blanks and for the proper scoring of such blanks in connection with the severing mechanism.

The nature of my improvements will be best 20 understood as described in connection with the drawings, in which they are illustrated, and in which—

Figure 1 is a plan view of the machine embodying my improvements in what I believe 25 to be their best and most efficacious form. Fig. 2 is a side elevation; Fig. 3, a side elevation taken as on the line 3 3 of Fig. 1; Fig. 4, a side elevation, on a larger scale, of the creasing devices forming part of the machine; 30 Fig. 5, a front elevation of said creasing devices; Fig. 6, a plan of the upper die; Fig. 7, a plan of the lower die. Fig. 7^a is a detached perspective view of a movable plate forming part of the lower die; Fig. 8, a cross-section through the dies on the line 8 8 of Fig. 35 4; Fig. 9, a cross-section through the dies on the line 9 9 of Fig. 4, Figs. 10 and 11 showing the operations performed upon the cardboard in passing through the dies of the machine.

A indicates the framing of the machine; B, the main driving-shaft, to which is attached the driven pulley B' and the gear-wheel B², which, through gear B³, communicates motion 45 to the lower shaft B⁴.

B⁵ is a gear-wheel driven by the gear B³ and communicating motion through the gears B⁶ and B⁸ to shafts indicated at B⁷ and B⁹. The gear B⁵ also engages the gear B¹⁰, and 50 through that gear and the engaged gear B¹² drives the shaft B¹¹ and B¹³. The gear B¹⁰ also actuates the gear B¹⁴, working on the stud B¹⁵ and through it and the gears B¹⁶ and B¹⁸ drives

the shafts B¹⁷ and B¹⁹. The gear B¹⁴ also communicates motion through the gears B²⁰ and 55 B²¹ to the gear-wheel B²² and its attached shaft B²³, the gear B²² engaging the gear B²⁴ on stud B²⁵ and through it driving the gears B²⁶ and B²⁸ and their attached shafts B²⁷ and B²⁹.

A' is the feed-table of the machine, A² indicating a guide at the side of said table for the proper alinement of sheets of cardboard.

C is a transversely-extending part of the framing of the machine, in which are formed transversely-extending guideways C' and C², 65 communicating their slots with the face and back of the frame-section C.

D is a similarly transversely extending part of the frame, having the transverse guideway D' also communicating through a slot with 70 the face of this section of the frame.

E E' are feed-rolls situated immediately in front of the table A' and secured on the shafts B²⁷ B²⁹.

G is a cutter-cylinder secured on the shaft 75 B²⁸ immediately below the rotatable cutter-blade H, which is secured on a slide H', vertically movable in a guideway I, which has an outwardly-extending arm I', through which extends the adjustable abutment-screw (indicated at I²) by means of which the vertical adjustment of the slide H' is regulated. The slide H' and guideway I are secured in place by the T-bolt I³, passing through both of them and having its head I⁴ secured in the guideway C'. It will readily be seen that by this construction the cutter can be transversely shifted at will and firmly secured in any desired place.

E' E' are feed-rolls secured on the shaft 90 B¹⁷ B¹⁹ in front of the cutter H.

F F are feed-rolls secured on the shafts B¹¹ and B¹³ and acting in immediate juxtaposition to the creasing devices, to be described.

E² E² are feed-rolls secured on the shafts B⁷ 95 and B⁹ in advance of the rolls F, and Q Q' are cutter-carrying cylinders secured to the shafts B and B⁴ and carrying the cutting-disks, (indicated at R and R'), which, being of a familiar type, need not be further described.

J indicates the adjustable support for the lower creasing-die. It is formed with a bolt-hole J', through which extends the T-headed bolt J', the head moving in the guideway D' and the nut acting to clamp the die-support 105 against the transverse framing portion D.

The die-support is also formed with a perforation J^3 , through which extends the shaft B^1 . To the upper end of this support J are secured the parallel die-sustaining walls, (indicated at 5 $K' K'$), die-plates $K^2 K^2$ being secured to the tops of these walls and shaped, as best shown in Fig. 7, so as to provide a V-shaped aperture, as shown at K^6 , between the proximate edges of the plates. The angling-walls are 10 indicated at $K^4 K^4$ and preferably terminate where they approach closest to each other in parallel continuations, (indicated at $K^5 K^5$). By preference the front edges of the plates $K^2 K^2$ are curved, as indicated at K^3 . 15 L is a plate of somewhat less breadth than the space between the walls $K' K'$ and having formed along the center of its upper surface the rib, (indicated at L'), preferably at its rear end, curved or bowed upward, as indicated at L^2 . This plate is normally held up in contact with the plates K^2 by the action of springs (indicated at $M M$) and is held against longitudinal movement by pins k , engaging openings l , formed in the base of the plate. 20 N is a slide having an outwardly-extending arm N' , a bolt perforation N^2 , and preferably a rearwardly-extending portion N^3 , which is adapted to fit in the front slot C^2 of the guide-frame C . Vertically movable in 25 this guideway N is the die-holding arm O , having a horizontal forward extension O' , to which the die proper is secured. The arm O is formed with a bolt perforation O^2 . The vertical adjustment of the arm O is regulated by the set-screw N^4 , and its horizontal adjustment, as well as its clamping in determined 30 position, is effected by the T-headed bolt N^5 , the head N^6 of which is engaged in the slot C^2 . 35 P is the die proper, secured on the lower faces of the arm O' and having a downwardly-extending portion P' , which at the rear end is formed with two parallel ridges $P^2 P^2$, which extend down into the wider V portion between the plates $K^2 K^2$ and embrace between them 40 the surface P^3 , which presses down against the curved portion L^2 of the rib L' . Beginning at the points indicated at P^6 in Fig. 6, the ribs P^2 are cut away above the level of the portion P^3 , which is continued as a rib P^4 , 45 preferably slightly dovetailed, adapted to extend into the narrower portion of the V, the portions $P^6 P^6$ on each side running parallel with and over the edges of the plates K^2 , where they approach closest together. 50 S I have indicated at S the cardboard in the process of being creased or scored, the cardboard being first bent to approximately the form indicated in Fig. 10 and then as it passes through the creasing-dies being bent to the 55 final form. (Indicated in Fig. 11.) 60 $S' S'$, Fig. 10, indicate the location of the bends over the rib portion L^2 at the wider portion of the V, and $S^2 S^2$ indicate the location of the bends in the cardboard effected at the 65 same stage of the operation over the ribs $P^2 P^2$,

while in Fig. 11 I show the final form of bends given the cardboard at the same locations or lines.

In operation the sheets of cardboard are fed in proper alignment over the table A' into the bite of the feed-rolls $E E$, which force the sheet forward between the cutter H and the cutter-cylinder G , these cutters being arranged, preferably, so as to sever the sheets into as many sections as there are scoring or creasing devices. The severed sheets are then drawn forward by the action of the feed-rolls $E' E'$, $F F$, and $E^2 E^2$ between the upper and lower scoring or creasing guides, the first operation performed upon the cardboard being 70 to bend it to approximately the shape shown in Fig. 10, and then as the paper passes forward the lines of fold are practically reversed until the final crease or score is of the kind indicated in Fig. 11. It will be noticed that by 75 this operation the cardboard is along the lines of the crease first bent in one and then in the other direction, thus effectually "breaking" the board and insuring a permanent score or crease, such as is desirable in the manufacture of paper boxes. The special conformations of the dies as shown in the drawings and above referred to are those found to give the best results, but may of course be departed from without variation from the real spirit 80 and scope of my invention. 85

It is obviously desirable that the angling-plates $K^2 K^2$ should be adjustable to and from each other to allow of the use of the scoring-die on cardboards of different thicknesses, and I provide for this by using washers or shims $T T$ of varying thickness. 90

The cutters $R R'$ are for the purpose of trimming the creased cardboard. 95

It is a characteristic feature of my machine that the cutting and scoring operations are progressive—that is to say, they take place while the sheets are being fed through the machine, beginning at their front edges and progressing through the moving sheets to 100 their rear edges. 110

Having now described my invention, what I claim as new, and desire to secure by Letters Patent, is—

1. A scoring device for cardboard, having 115 in combination with means for feeding sheets of cardboard between fixed dies, a die over and through which the cardboard is passed, said die having an aperture with walls approaching each other in the direction of travel 120 of the cardboard, and a coacting die having a tongue extending into the aperture of the first die and about which tongue the cardboard is progressively folded by the action of the converging walls of the first die. 125

2. A scoring device for cardboard having in combination with means for feeding sheets of cardboard between dies a die having a V-shaped aperture and an elastically-supported central rib lying within said aperture, and a 130

coacting die having a tongue extending into said aperture between which and the rib aforesaid the cardboard is fed and about which the cardboard is progressively folded by the converging walls of the first die.

3. A scoring device for cardboard having in combination with means for feeding sheets of cardboard between dies a die provided with a V-shaped aperture and a centrally-disposed rib, and a coacting die having a tongue extending into the aperture of the first die said tongue, in the part lying in the wider part of the aperture, having two projecting ribs adapted to press the board over the edges of the rib of the first die and said tongue having also in its part lying within the narrow part of the aperture a single centrally-disposed rib over which the board is folded by the walls of the aperture.

20 4. A scoring device for cardboard having in combination with means for feeding sheets of cardboard between dies a die provided with a V-shaped aperture and a centrally-disposed elastically-supported rib, and a coacting die having a tongue extending into the aperture of the first die said tongue in the part lying in

the wider part of the aperture having two projecting ribs adapted to press the board over the edges of the rib of the first die and said tongue having also, in its part lying within the narrow part of the aperture, a single centrally-disposed rib over which the board is folded by the walls of the aperture.

5. A scoring device for cardboard having in combination with means for feeding sheets of cardboard between dies a die provided with a V-shaped aperture and a centrally-disposed elastically-supported rib having a curved and elevated rear portion L^2 , and a coacting die having a tongue extending into the aperture of the first die, said tongue in the part lying in the wider part of the aperture having two projecting ribs adapted to press the board over the edges of the rib of the first die and said tongue having also in its part lying within the narrow part of the aperture, a single centrally-disposed rib over which the board is folded by the walls of the aperture.

JOHN NAZEL.
